MACHINE FOR LAPING TOOTHED ELEMENTS

John M. Christman, Detroit, Mich., assignor to
Packard Motor Car Company, Detroit, Mich., a
corporation of Michigan

Application April 22, 1935, Serial No. 17,728
Renewed May 9, 1938

29 Claims. (Cl. 51—157)

This invention relates to apparatus for improving radially toothed machine elements such as gears and the like and is more particularly concerned with the lapping or grinding of gear teeth after the formation of the teeth by the usual milling or cutting operations.

It is common practice in the art to which this invention relates to improve the meshing of toothed gears by a lapping operation which involves the engaging of the gears with a lap member having corresponding teeth and effecting relative reciprocation between the gear and the lap member, a suitable abrasive being supplied to the cooperating toothed surfaces. For example, an externally toothed gear and an internally toothed lap, the latter being preferably hardened and having teeth affording therebetween recesses within which the gear teeth may be received snugly or with a slight clearance, are relatively aligned axially and are reciprocated in an axial direction, means being provided to simultaneously urge one of the cooperating members to rotate with respect to the other to apply slight circumferential pressure between the cooperating teeth. Again, lapping of gears is sometimes effected by rolling a gear and a toothed lap in meshing relation, relative axial reciprocation of the gear and lap during rotation thereof being additionally applied if desired. In such an arrangement the circumferential pressure between the cooperating teeth may be that resulting from the driving of the gear by the lap or vice versa.

It has been proposed heretofore to establish the amount of circumferential pressure applied between the cooperating teeth of the gear and lap by mechanical means, for instance by a spring device for yieldingly applying torque to the cooperating gear and lap. In practice, however, such machines have not proven wholly satisfactory, principally because of the failure of such devices to determine in advance the extent to which the grinding operation is to be carried out. Thus it is obvious that any satisfactory apparatus for controlling the lapping of a gear must be so constructed that a definite amount of material and no more will be removed from the faces of the gear teeth undergoing treatment; lack of uniformity in the depth of grinding produces gears which mesh either with too little or too great clearance.

For these and other reasons it is proposed as one form of the present invention to provide a lapping machine which is manually controlled, a skilled operator applying circumferential pres-

sure to the gear and lap by hand, the amount of pressure and the amount of material removed from the gear during the process being determined by the operator's sense of touch. The necessarily delicate control of such machines is facilitated by reorganization of the arrangement and modification of the construction of the component parts of the machine, as hereinafter more fully described.

Machines of this character in which the circumferential pressure is controlled manually have been constructed and are now fairly extensively used, but the maximum speed at which these machines can be operated is relatively low and the output correspondingly small. Thus it is found that when a certain maximum speed is exceeded, very damaging vibrations are induced, the whole machine shaking so violently that further increase in speed of operation would be dangerous and would obviously interfere with the control of the pressure by the operator's sense of touch.

With machines constructed in accordance with the instant disclosure it is found that smooth operation can be secured when the machine is running at a speed more than three times greater than the normal speed of previously constructed machines. For example, it has been found by actual comparison of a machine of the old type and a machine constructed in accordance with the present invention that when the gear is reciprocated in the old machine at the rate of 210 strokes per minute, the operation is wholly satisfactory, this being the normal speed for which the machine is constructed. When the speed of the old machine is increased to 370 strokes per minute, the lapping operation can be carried out with a fair degree of success, but the machine vibrates at a dangerous amplitude, and it is quite apparent that long continued operation at this speed would seriously damage the machine.

A machine constructed in accordance with the present invention, on the contrary, was originally designed to operate at 570 strokes per minute, and the speed has been increased to 712 strokes per minute without the development of disturbing vibrations, the operation being so smooth that it is quite apparent that further substantial increase in speed may be obtained without giving rise to vibrations of serious and damaging amplitude.

The invention further contemplates the provision of a machine of this character employing a fixed lap and a reciprocating gear support in

which the circumferential pressure between the gear and lap is secured by the application of torque to the gear support rather than to the lap, whereby the entry of oil and abrasive into the mechanism for applying such pressure may be more readily avoided, the construction simplified, and manual operation rendered more convenient. It is a further feature of the invention that the replacement of worn laps and the accurate alignment of the gear and lap are facilitated.

It is obvious that machines in which the working pressure is manually applied place much reliance on the skill of the operator and that only the trained operator will be able to effect accurate control of the lapping of gears having different degrees of irregularity and to detect in such gears solely by his sense of touch the extent to which grinding has proceeded.

Thus it is a further object of the present invention to eliminate the human factor in the lapping of gears and to provide a machine which is automatically operable to determine with accuracy both the pressure applied between the cooperating teeth of the gear and lap and the extent to which the grinding operation is allowed to proceed or the amount of material which is to be removed from the gear being treated. It is a still further object to provide a gear lapping machine in which the direction of applied circumferential pressure is automatically reversed.

In the lapping of gears by any of the conventional methods, clearance is usually provided between the cooperating teeth of the gear and lap; even in the absence of such clearance there is inevitably some lost motion or backlash in the mechanism whereby pressure is applied between the opposing faces of the teeth. Thus it is essential in a machine which is to function automatically to apply this pressure and to periodically reverse the same that this clearance be taken into consideration in determining the extent to which the gear and lap will be relatively rotated when the pressure is shifted, and to permit the gear and lap to partake of an additional relative rotative movement corresponding to the amount of material that it is desired to remove. Since the clearance or backlash necessarily varies in different unlapped gears, it is obvious that the extent of relative rotation of the gear and lap from the position which they occupy when one side of the gear teeth have been ground to the position which they occupy when the grinding of the other side has been completed will vary on each operation. It is one of the purposes of the present invention to compensate for this variation and to ensure that regardless of the extent of clearance present, a substantially fixed amount of material will be removed from each working face of the gear teeth.

Further objects and features of the invention will be apparent from the following description taken in connection with the accompanying drawings, in which

Figure 1 is a side elevation of a gear lapping machine constructed in accordance with the principles of the invention;

Figure 25 is a sectional view taken substantially on the line 25-25 of Figure 14.

In order to facilitate an understanding of the invention, reference is made to the embodiment thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

While various features of the invention are applicable to gear lapping machines of other types, as hereinbefore explained, the preferred form of the invention as shown in Figure 1 involves the method of lapping gears by imparting relative reciprocal movement to a gear and a lap. More specifically, the machine disclosed in Figure 1 is of the type in which the lap is provided with an internal toothed portion and is retained against movement, the gear having external teeth and being reciprocated in meshing relation with the lap. Thus the machine may comprise a frame including a base 30 and a head portion 31 overlying the base, the head portion being supported by a standard 32 rising from the base. A shaft 35 having at its lower end a reduced portion 33 adapted to receive a gear 37 to be lapped, the latter being secured in position by means of a nut 38 or in any other conventional manner, is clamped or otherwise secured in position in a bracket 40. The bracket and clamping device are hereinafter described more fully, it being sufficient to state at this point that the arrangement is such as to facilitate the application to and the removal from the bracket of the shaft 35 and the associated gear 37.

The bracket 40 is provided with an upwardly directed boss 41 which may be keyed or otherwise secured as at 42 against rotation on a shaft 44. A sleeve 46 threaded on the shaft 44 is provided at its lower end with an annular flange 43

which is arranged to be gripped between a co-operating flange on a collar 49 and the upper end of the boss 41, the collar having threaded engagement with the boss. The bracket 40 is thus firmly secured to the shaft 44 for rotation and reciprocation therewith, but the rigidity of the connection may be increased and the possibility that play may develop as the result of wear may be eliminated by further clamping the boss 41 to the shaft 44 as shown in Figures 11 and 13. Thus a wedge member 52 seated in an aperture in the boss 41 may be drawn into binding engagement with the shaft 44 by a bolt 53 having threaded engagement with the wedge member.

As shown more particularly in Figures 2 and 3, the shaft 44 is supported adjacent the upper end thereof in a bearing guide 55 and is operatively connected by means of a pitman 58 to an eccentric 59 formed on or secured to a shaft 60, the latter being carried by the head portion of the frame and having secured thereto at its outer end a pulley 62 which may be driven by a belt 63 from a motor 65.

It will be appreciated that by means of the mechanism thus far described, rotation of the shaft 60 will effect reciprocation of the shaft 44, the bracket 40, the shaft 35, and the gear 37 to be lapped, gear 37 meshing during the operation with a stationary lap 68 which may be supported rigidly on the base 30 of the frame in the manner described more in detail hereinafter. Preferably the eccentricity of the member 59 is sufficient to ensure a fairly long stroke of the gear 37. For instance, while it is preferred that the gear 37 shall not be actually disengaged from the lap 68 at either end of the stroke of the gear, the length of the stroke may be greater than half the thickness of the gear as measured axially, substantial bodily displacement as distinguished from mere vibratory movement being imparted to the gear so as to ensure maximum relative linear speed of the contacting toothed surfaces of the gear and lap and to promote uniformity of abrading action.

It is due in large measure to the coordination of the several parts of the mechanism by disposition thereof in the manner indicated in the drawings that the high speed of operation hereinbefore referred to is attained. Thus it is important that the means for effecting reciprocation of the gear to be lapped and of the shafts which support the same be located substantially adjacent the upper ends of these shafts, and that the means which serves to guide the shafts during reciprocation, and which may also be employed for the purpose of applying pressure between the cooperating teeth of the gear and lap, be disposed at a lower point, and preferably fairly close to the gear and lap.

Guide means of this character, of which the principal function is to ensure proper control of the gear to enable the teeth thereof to follow the teeth of the lap, is associated with either of the shafts 35 and 44, and preferably the latter. For instance, if the gear and lap have straight teeth, it is desirable to prevent rotation of the shafts 44 and 35 during reciprocation thereof, whereas if the gear and lap have twisted or helical teeth, or are of some other configuration, the shafts should be rotated accordingly on their own axis during reciprocation.

Various devices may be employed for this purpose, but in the preferred form of the invention the guide means comprises one or more cooper-

ating tongue and groove elements, such elements constituting in effect a cam device in the event the teeth of the gear and lap are not straight. Thus the shaft 44 may be provided with an enlarged portion having generally axially directed teeth 70 thereon, these teeth cooperating with corresponding internal teeth on a sleeve 75 which surrounds the shaft, an inner sleeve 72 of bearing metal being preferably cast within the sleeve 75 for this purpose, right and left-hand spiral grooves 73 being formed in the inner surface of the sleeve 75 to lock the bearing metal against displacement with respect to the sleeve. Since the invention is illustrated as applied to the lapping of a helically toothed gear, the teeth 70 are constructed to afford a corresponding helix angle, it being understood that in the event a gear having straight teeth is being lapped, the teeth 70 will be correspondingly straight.

The sleeve 75 is supported for rotation in the head portion of the frame and it is provided at its lower end with an annular flange 76 having a toothed periphery which is engaged by a rack 78, the latter being supported for reciprocation in a substantially horizontal plane. In lieu of the rack 78, which may be reciprocated in a manner hereinafter described by mechanism operable automatically to control the abrading action, an arrangement such as that shown in Figure 16 may be employed in which the flange 76 of the sleeve 75 is provided with a toothed portion arranged to cooperate with a worm 79, the latter being secured to a shaft 80 which is rotatable manually by means of a hand wheel 82. A flexible element 84 may be provided at the lower end of the head portion of the frame to prevent the discharge of lubricant therefrom without interfering with the reciprocal and rotary movements of the shaft 44 and to seal the cooperating toothed elements 70, 72 and 76 against the entry of dust, lapping compound, or other foreign and abrasive material.

In order that the shaft 44 may be permitted to rotate freely without disturbing the connection thereof to the shaft 60, the shaft 44 may be formed above the threaded portion 70 thereof in two sections, for instance as shown in Figure 9, any conventional type of rotating coupling such as that indicated generally at 71 being introduced between the two sections of the shaft.

Assuming that the sleeve 75 is held against rotation, the shaft 44 will be rotated during vertical reciprocation thereof by reason of the co-operation of the teeth 70 of the shaft with the corresponding teeth on the sleeve. When, however, the sleeve 75 is rotated by reciprocation of the rack 78 or by rotation of the hand wheel 82 and worm 79, the sleeve will act through the teeth 70 to effect a slight rotation of the shaft 44 in one direction or the other. Thus the bracket 40, shaft 35, and gear 37 may be rotated to an extent sufficient to apply pressure between one side of the cooperating gear teeth on the lap 68 and gear 37, the pressure so applied preferably being sufficient to ensure reasonably rapid abrasive action while insufficient to cause the extrusion from between the cooperating teeth of the lap and gear of the abrasive material usually employed in machines of this character.

As hereinbefore explained, the amount of working pressure applied has until now been left largely to the discretion of the skilled operator in charge of the machine and it is essential that the amount of pressure be accurately regulated. Thus while the mechanism provided for this

purpose may be associated with the lap to apply torque thereto, it is preferably disposed above the base of the machine and arranged to operate directly upon the gear being lapped in order to avoid the discharge of abrasive and of particles of the removed material on and into the mechanism. At the same time it is desirable that this mechanism should be located at a point as close to the lap as is possible, bearing in mind the fact that the machine may be required for the lapping of gear clusters and the like having considerable length. Thus machines of this character are intended to perform delicate operations requiring very small tolerances and if circumferential pressure is supplied to the gear supporting shaft at a point considerably above the gear and lap, the torsional elasticity of the shaft may be sufficient to prevent accurate work. Therefore the necessary circumferential pressure is preferably applied by mechanism such as shown in Figure 9 through sleeve 75, the cooperating helical threads on the sleeve and gear supporting shaft being sufficiently close to the gear and lap to prevent undesirable torsional springing of the shaft.

Returning to the bracket 40, it will be observed that this bracket is generally U-shaped in horizontal section and is provided on each of the two flat sides thereof with vertically disposed guide strips 86 defining common vertical planes. At the lower end of the bracket 40 is secured a plate 87 having an aperture 88 therein which is open at the front side. The plate 87 is further provided with a substantially conical seat 90 arranged to engage a corresponding seat on a member 91, the latter being pinned or otherwise secured as at 92 to the upper end of the shaft 35. A generally rectangular member 94 surrounds and partially overlies the upper end of the member 91 and is received snugly within the bracket 40, being retained against rotation therein by engagement with the guide strips 86. A plurality of friction plates 96, of which alternate plates are keyed to the members 94 and 91, are interposed between these members and function as a frictional coupling therebetween to normally prevent relative rotation thereof. Seated on the upper face of the member 94 is a plate 97 having a hardened insert 98 in the central portion thereof against which pressure may be applied to increase the frictional contact of the interleaved plates 96.

The principal purpose of this arrangement is to facilitate indexing of the gear, it being advisable to register the teeth of the gear with different lap teeth so that greater uniformity of tooth contour may be secured by averaging the defects of the teeth of the lap and gear. Thus with the present construction this may be readily accomplished by releasing the pressure applied to the plate 97 in the manner hereinafter described and raising the shaft 35 manually to withdraw the gear 37 from engagement with the lap. When thus withdrawn the gear may be rotated to a new position and replaced in meshing relation with the lap, the friction connection between the bracket 40 and the shaft 35 permitting the firm retention of the latter in any position of rotative adjustment with respect to the bracket 40.

Adjacent the upper end of the bracket 40, extending from one side wall of the bracket to the other and journalled therein, is a spindle 100 provided with a handle 101 whereby the same may be rotated. The spindle 100 is pro-

vided with an eccentric portion 103 on which is journalled an arm 104 depending from the shaft and carrying at its lower end an adjustable abutment 105 which is adapted to engage the plate 97 and to apply pressure thereto when the handle 101 is rotated in one direction and which may be withdrawn from the plate by rotation of the handle in the other direction. In order that the arm 104 may be readily withdrawn from the plate 97 to facilitate the withdrawal of the shaft 35 from the bracket 40 for the replacement of gears 37 and to permit release of the shaft for indexing, a spring 106 is provided, this spring being secured at one end to the arm 104 and at the other end to a sleeve 107 which is secured to the eccentric portion of the shaft 100. This spring is under sufficient tension to swing the arm 104 forwardly and upwardly as soon as pressure between this arm and the plate 97 is released. In order that the arm 104 may be readily returned to its operative position, that portion of the arm which surrounds the spindle 100 is provided with an annular recess 109 and an abutment 110 secured to the spindle 100 is arranged to ride in this recess, the arrangement being such that as the handle 101 is rotated toward the position in which pressure is exerted downwardly on the arm 104, the arm 104 is swung toward its operative position by engagement of the abutment 110 with the arm 104 at one end of the recess 109.

While the lap 68 may be secured in position in any conventional manner, the arrangement shown in Figures 11 and 12 is preferred. This arrangement includes a catch basin 112 which is supported in the base 30 of the frame, and an annular element 113 resting on the upper flange 114 of the catch basin. The element 113 is provided with an annular recess affording a substantially horizontal surface 116 and a generally cylindrical surface 117, these surfaces being accurately machined and centered with respect to the axis of the shaft 35. Corresponding accurately finished surfaces are provided on the lap 68 which seats therein, an annular passage 119 communicating with downwardly directed discharge passages 120 being formed in the member 113 so that abrasive, oil, dirt, and the like may be readily removed from the surfaces 116 and 117 with which the lap engages. A bell-crank 112, pivotally supported on the base 30, is provided for use in raising and lowering the catch basin 112.

The upper surface of the lap is engaged by a plurality of clamp elements 121, each of which is seated at its outer end on the element 113, and at its inner end with the lap 68, and is provided intermediate its ends with an aperture 122 through which a bolt 124 may extend, the bolts being threaded in the element 113. The lap may be thus placed in accurate alignment with the gear undergoing treatment and is frictionally clamped on the base 30 of the frame against unintentional displacement.

The catch basin 112 may be filled or nearly filled with an abrasive mixture, for instance emery in suspension in oil, and thus on each downward stroke of the gear 37 a small quantity of the abrasive is supplied to the toothed portion of the gear. In order that the emery may not settle but will remain in generally uniform suspension, a pipe 115 may be fitted into the lower end of the catch basin and compressed air discharged through this pipe into the mixture so that the latter is maintained in a state of agi-

tation. The compressed air may be derived from any source; for instance by a small pump driven from the burnishing machine.

The machine thus far described is so constructed as to provide either for manual or automatic control of the working pressure applied to the working faces of the gear and lap and as the result of the simplicity of the construction, extremely high speeds of operation are possible without the development of annoying or serious vibration. It is important to note that reciprocation of the gear is effected by a simple non-adjustable crank and pitman drive imparting a fixed reciprocal stroke to the gear supporting shaft. The use of cumbersome mechanism for displacing or altering the length of the stroke is avoided, it having been found that the inclusion of mechanism of this character contributes largely to the development of the harmful vibrations hereinbefore referred to. When applied to the lapping of gears having helical teeth, the necessary rotation of the gear supporting shaft during reciprocation thereof and the application of torque for applying the working pressure are both effected in such manner that inaccurate operation as the result of torsional elasticity of the gear supporting shaft is prevented. While the moving parts have sufficient rigidity and strength for the intended purpose, the mass of those parts which execute reciprocating movement may be reduced to a minimum with consequent reduction in vibration.

An automatic pressure applying mechanism is illustrated in Figure 4 and includes a shaft 130 to which the rack 78 may be directly secured, the shaft 130 extending within a casing 131 carried by the head portion 31 of the frame. The casing 131 is provided with a cylindrical bore in which is slidably supported a cylinder 132 having an integral head 133 at one end thereof and a removable head 134 at the other end, suitable packing means indicated at 135 to permit the passage of the shaft 130 therethrough and to seal the interior of the cylinder being provided. Fluid pressure conduits 136 and 137 communicate with the interior of the cylinder at either end through ports in the cylinder heads 133 and 134 respectively. The cylinder 132 is normally retained against axial displacement in the housing 131 by a plurality of friction elements 140, each such element being supported in an aperture in the housing and being pressed into engagement with the adjacent wall of the cylinder 132 by means of a coil spring 142, the degree of compression of the latter being adjustable by means of the threaded abutment 143.

Fitting within the cylinder is a piston 145 which is slidable therein in a conventional manner, the piston being hollow and having end walls 147 and 148, the latter being detachable. The shaft 130 extends through the piston and sleeves 150 and 151, slidably mounted on the shaft 130, are disposed within the piston 145, these sleeves having abutments on their outer ends in the form of nuts 153 and 152 which are threaded on the respective sleeves and which may engage the outer faces of the end walls 147 and 148 of the piston.

Located within the piston 145 and secured to the shaft 130 substantially centrally of the piston is an abutment 154. The sleeves 150 and 151 are retained in engagement with this abutment by means of coil springs 156 and 157, these springs engaging at their opposite ends the respective end walls 147 and 148 of the piston.

Each sleeve is constructed to provide a shoulder which, in the position which the parts occupy in Figure 4 of the drawings, is spaced from the adjacent end wall of the casing to a slight extent. Thus a clearance space 159 is afforded between the sleeve 150 and the end wall 147 of the piston and a clearance space 160 is afforded between the sleeve 151 and the end wall 148 of the piston to permit axial movement of the sleeves with respect to the piston.

Means are provided for alternately supplying fluid, for instance air, under pressure to the opposite ends of the cylinder 132 through the conduits 136 and 137. Thus each of these conduits 15 is connected through a flexible hose or the like to a valve casing 162 within which is disposed a rotatable valve element 163. The valve element 163 is provided at its periphery with passages 165 and 166 each extending partly around the element. The passage 166 communicates through a passage 168 with the outer surface of the valve element and thus constitutes a vent to atmosphere. The passage 165 communicates through a passage 169 with a conduit 170 through which air under pressure is supplied. The conduit 136 is in communication with a port 172 extending through the valve casing and arranged to communicate with the passages 165 and 166 successively as the valve element 163 is rotated, and conduit 137 similarly communicates with the passages 165 and 166 successively through a port 173. The valve element 163 may be secured in position within the casing by means of a nut 175 threaded on one end thereof and may be rotated by means of a worm gear 176 which may be formed integrally therewith. Engaging the worm gear is a worm 178 secured to or formed on a shaft 179 which is suitably supported on the frame, the shaft 179 having secured thereto a pulley 180 which may be driven by means of a belt 182 from a pulley 183 secured on the shaft 60 hereinbefore described.

The operation of the structure shown in Figure 4 will be apparent from an inspection of diagrammatic Figures 17 to 23 inclusive which illustrate the successive positions assumed by the component parts of the structure. Thus in Figure 17 the parts are shown in the position which they occupy immediately prior to the reversal of the direction of torque applied to the gear 37 for the purpose of lapping the opposite faces of the teeth thereof. It will be seen that the piston 145 occupies a position to the extreme left, the cylinder 132 is at the extreme right of its movement with the end wall 134 thereof in engagement with the left end of the piston, and the abutment 154 occupies an intermediate position with respect to the end walls 147 and 148 of the piston, neither of the springs 156 or 157 being capable of expansion to displace the abutment 154. Air or other fluid under pressure is now admitted to the left-hand end of the cylinder 132 through the conduit 136, the right-hand end of the cylinder being vented to the atmosphere. This result is achieved by the rotation of the valve element 163 to a position in which the passage 165 to which compressed air is supplied is just entering into communication with the conduit 136 while the passage 166 which is vented is just entering into communication with the conduit 137. Communication of the passages 165 and 166 with the conduits 136 and 137 respectively will now be maintained until the valve element 163 has rotated through nearly 180°.

The piston 145 will now be displaced to the right, compressing the spring 157 and shifting the rack 78 to effect rotative displacement of the gear 37 to the extent necessary to contact the opposite working faces of the gear teeth with the opposed faces of the lap 68. Further displacement of the piston 145 to the right is prevented since the gear 37 which is directly connected to the abutment 154 can partake of no further displacement. While this clearance between the teeth of the gear and lap is being taken up by movement of the piston 145, the cylinder 132 is retained against movement by the friction elements 140, the elimination of clearance between the cooperating teeth and the compression of the spring 157 requiring little effort as compared with the force required to displace the cylinder 132 against the action of the friction elements 140. The parts now occupy the position in which they are shown in Figure 18 of the drawings.

It is not desired that the pressure of the air introduced in the cylinder 132 will be exerted between the teeth of the gear and lap since variation in the pressure of the air supplied would result in lack of uniformity in the grinding operation and the delicate pressure which is important in an operation of this character is difficult to secure by the use of compressed air, it being intended that reliance shall be placed solely on the spring 157 for exerting the necessary pressure between the cooperating teeth. Thus when the parts have assumed the position shown in Fig. 18, the cylinder 132 is displaced to the left by the action of the compressed air between the end wall 148 of the piston and the cylinder head 134, the air pressure building up to the extent necessary to overcome the resistance of the friction elements 140. Displacement of the cylinder 132 to the left is limited by engagement of the cylinder head 133 with the end wall 147 of the piston, the position of the parts being shown in Figure 19. It will now be observed that the spring 157 is still under compression, and this spring will gradually expand as material is removed by the abrasive action between the teeth and the gear and lap, expansion of the spring being limited by engagement of the nuts 152 on the sleeve 151 with the end wall 148 of the piston when the parts occupy the position in which they are shown in Figure 20.

When expansion of the spring 157 is completed, no further pressure will be applied between the teeth of the gear and lap and the amount of material removed therefrom may thus be accurately determined in advance by establishment of the clearance 160 between the sleeve 151 and the end wall 148 of the piston. While adjustment of this clearance is ordinarily not necessary, it is obvious that the clearance may be readily altered if desired by the use of shims intermediate the abutment 154 and the sleeve 151, suitable adjustment of the nuts 152 being effected.

Ordinarily the grinding operation on the engaged working faces of the gear teeth will be completed before the valve element 163 has rotated through 180°, which permits the execution of several lapping strokes without the application of pressure between the teeth of the gear and lap. On completion of such rotation, conduit 136 will be vented to relieve the pressure in the left-hand end of the piston and conduit 137 will be supplied with air under pressure in a manner readily understood. The reverse

series of operations will now take place, the gear 37 being first displaced to take up clearance between the teeth of the gear and lap and backlash in the connections between the gear and the abutment 154, and the spring 156 will be compressed to apply the pressure necessary for proper abrasive action between the cooperating teeth. The successive positions of the parts during these reversed operations are shown in Figures 21 to 23 inclusive and need not be described, the fourth and last position being of course that corresponding to Figure 17. At this point, since grinding has been completed to the required extent, the operation of the machine may be interrupted, some suitable indicating device being employed, if desired, to warn the operator that the end of the cycle has been reached, or the mechanism may be adjusted to permit the grinding of each of the working faces of the gear teeth several times before the desired amount of material is removed. In lieu of the employment of an indicating device, the supply of pressure fluid may be interrupted, for example by the provision of a slip or friction coupling in the gearing which rotates the valve element 163 and cooperating abutments on the frame and on the gear 176 or valve element, one of these abutments being manually movable so that operation may be resumed when desired. Ordinarily, however, several cycles of operation are completed before the gear is finally finished, the gear being periodically indexed with respect to the lap in order to obtain greater uniformity of contour of the working faces of the gear teeth as hereinbefore described. While the grinding may be continued to any desired extent, the operator is enabled without relying on his sense of touch to determine at any stage precisely to what extent the grinding is completed.

In order that production may be speeded up and the cost of construction and expense of operation reduced to a minimum, it is desirable to provide a battery of these machines such as shown in Figure 24 in which a number of gears may be simultaneously lapped, the mechanism for controlling the lapping of each gear being driven from a common motor 65 and the supply of compressed air being regulated by valve mechanism within a single valve casing 162. In view of the general similarity of construction shown in Figure 24 with that hereinbefore described, similar reference numerals are employed. Thus reciprocation of each of the gears being lapped is effected through a common drive shaft 185, bevel gears 186 being provided to drive the several operating shafts 60 of the lapping units from this shaft. The shaft 185 is operable by belt gearing from the motor 65, the shaft 179 which drives the worm gear 176 controlling the valve mechanism being operable through belt gearing from the shaft 185.

While a single valve casing 162 may be placed in communication with the cylinders within the several fluid pressure casings 131 by suitable conduits, not shown in the drawings, it may be found desirable in order to avoid the delayed action resulting from the time required to build up pressure through a relatively long conduit and to vent to atmosphere therethrough, to supply separate valve casings 162 for each of the units of the series, the valve elements within these casings being driven from a common shaft 179 which is supported in the frame and extends transversely of and at the rear of the units.

It will be apparent from the foregoing description that certain features of the invention are equally applicable to machines in which the circumferential tooth pressure is applied manually as to machines in which this pressure is automatically controlled. It will further be apparent that the devices for automatically reversing the relative circumferential positions of the gear and lap and for applying pressure between the opposite working faces of the teeth thereof may be employed in lapping machines which are quite different in structure and function as regards the relative shape and arrangement of the lap and gear and the relative movements applied to these members. It is therefore intended that the scope of the invention shall not be limited otherwise than as defined in the appended claims.

Having thus described the invention, what is claimed as new and desired to be secured by Letters Patent is:

1. In apparatus for lapping gears of the type comprising mechanism for imparting relative motion to a lap member and a gear member having intermeshed toothed portions, the combination with means for applying torque to said members to establish circumferential pressure between the toothed portions thereof, of means operatively associated with said first named means for interrupting the application of such torque thereby on completion of a predetermined relative rotative displacement of said members resulting from the removal of material from the toothed portions thereof, and means operable in timed relation with said mechanism and associated with said first named means for reversing the direction of applied torque.

2. In apparatus for lapping gears of the type comprising mechanism for imparting relative motion to a lap member and a gear member having intermeshed toothed portions, the combination with means for applying torque to said members to establish circumferential pressure between the toothed portions thereof, of means associated with said first named means and operable in timed relation with said mechanism for periodically reversing the direction of applied torque.

3. The combination claimed in claim 2 in which a common source of motive power is provided to drive said mechanism and said last named means.

4. In apparatus for lapping gears of the type comprising mechanism for imparting relative motion to a lap member and a gear member having intermeshed toothed portions, the combination with means for effecting relative rotation of said members to the extent required to engage one working face of the teeth of the gear member with the opposed working face of the teeth of the lap member and for applying pressure between the said engaged tooth faces, said means including an element displaceable to the extent required to engage the cooperating tooth faces of the lap and gear members, and a second element displaceable with said first element in engaging the said tooth faces, said second element being further displaceable with respect to said first element to an extent sufficient to maintain the pressure between the engaged faces during removal of material therefrom, and means driven in timed relation with said mechanism for periodically reversing the direction of displacement of said elements to lap opposite faces of the teeth of the gear member.

5. In apparatus for lapping gears of the type

comprising mechanism for imparting relative motion to a lap member and a gear member having intermeshed toothed portions, the combination with means for effecting relative rotation of said members to the extent required to engage one working face of the teeth of the gear member with the opposed working face of the teeth of the lap member and for applying pressure between the said engaged tooth faces, said means including an element displaceable to the extent required to engage the cooperating tooth faces of the lap and gear members, and a second element displaceable with said first element in engaging the said tooth faces, said second element being further displaceable with respect to said first element to an extent sufficient to maintain the pressure between the engaged faces during removal of material therefrom, means for limiting the extent of displacement of said second element, whereby the amount of material removed from the opposed tooth faces of said members may be predetermined, and means driven in timed relation with said mechanism for periodically reversing the direction of displacement of said elements to lap opposite faces of the teeth of the gear member.

6. In a mechanical movement, the combination with a member supported for reciprocal movement, of means for applying force to said member tending to reciprocate the same, said means including a piston having a resilient connection with said member, a cylinder in which said piston is disposed to afford a working chamber at either side of the piston, said cylinder being supported for axial displacement limited in either direction by said piston, means yieldably restraining said cylinder against axial displacement, and means for alternately admitting fluid under pressure to opposite sides of said piston, whereby on the admission of pressure fluid to said cylinder at either side of said piston, said resilient connection will be stressed and said cylinder displaced to the extent of movement thereof to render the fluid pressure ineffective.

7. In a mechanical movement, the combination with a member supported for reciprocal movement, of means for applying force to said member tending to reciprocate the same, said means including a piston having a resilient connection with said member, a cylinder in which said piston is disposed to afford a working chamber at either side of the piston, said cylinder being supported for axial displacement limited in either direction by said piston, means yieldably restraining said cylinder against axial displacement, said last named means being sufficiently effective to restrain the cylinder against the action of said resilient connection when the latter is stressed, and means for alternately admitting fluid under pressure to opposite sides of said piston, whereby on the admission of pressure fluid to said cylinder at either side of said piston, said resilient connection will be stressed and said cylinder displaced to the extent of movement thereof to render the fluid pressure ineffective.

8. In apparatus for lapping the teeth of external helically toothed gears, the combination with a lap support, of an internally toothed lap carried in fixed position by said support, a frame having a portion extending above said support, a shaft supported on said frame for substantially vertical reciprocatory movement and for rotation about a substantially vertical axis, said shaft having a portion adapted to support a gear to be lapped in meshing relation with said lap, means

associated with said frame for imparting rotation to said shaft during reciprocatory movement thereof, said means including a sleeve having a helical toothed connection with said shaft, means for maintaining said sleeve against displacement axially of the shaft, and means for rotating said sleeve, whereby circumferential pressure may be applied to the cooperating teeth of the gear and lap.

9. In a machine for lapping helically toothed gears, the combination with a lap and a lap support, of means for securing said lap in fixed position on said support, a gear supporting shaft having the axis thereof coinciding with the axis of the lap and carrying a gear in meshing relation with said lap, a carrier for said shaft supported for reciprocating movement, a crank and pitman drive for said carrier, and means for imparting rotation to said shaft, said means including a normally fixed member, a helical cam connection between said carrier and said fixed member, a rotative coupling between said carrier and said crank and pitman drive therefor, and means for displacing said fixed member to apply torque to said carrier and shaft, whereby pressure may be applied to the cooperating working faces of the gear and lap.

10. In a gear lapping machine, the combination with a toothed lap member, of a support for said member, a support for a toothed gear member to be lapped, said supports carrying said members in intermeshing relation, means for reciprocating at least one of said supports and the member carried thereby, and guide means associated with a reciprocated support for constraining the latter to follow the generally axial direction of the teeth of the gear and lap members during such reciprocation, said means for reciprocating said support being disposed above said guide means and being operatively connected with said support adjacent the upper end of the latter.

11. In apparatus for lapping the teeth of external helically toothed gears, the combination with a lap support, of an internally toothed lap carried in fixed position by said support, a frame having a portion extending above said support, a shaft supported on said frame for substantially vertical reciprocatory movement and for rotation about a substantially vertical axis, said shaft having a portion adapted to support a gear to be lapped in meshing relation with said lap guide means associated with said frame for imparting rotation to said shaft during reciprocatory movement thereof, said means being operatively connected with said shaft above and in proximity to said lap, and means carried by said frame and operatively connected with the upper end of said shaft for reciprocating the latter, said last named means comprising a crank and pitman device having a fixed, non-adjustable throw.

12. In a gear lapping machine, the combination with a toothed lap member, of a support for said member, a support for a toothed gear member to be lapped, said supports carrying said members in intermeshing relation, means for reciprocating at least one of said supports and the member carried thereby, a basin disposed beneath said members and adapted to receive a mechanical suspension of abrasive material in liquid to a level sufficient to ensure the wetting of the reciprocated member in the lower position of the latter, and means for agitating the liquid to prevent the abrasive from settling.

13. In a gear lapping machine, the combination with a toothed lap member, of a support

for said member, a support for a toothed gear member to be lapped, said supports carrying said members in intermeshing relation, means for reciprocating at least one of said supports and the member carried thereby, a basin disposed beneath said members and adapted to receive a mechanical suspension of abrasive material in liquid to a level sufficient to ensure the wetting of the reciprocated member in the lower position of the latter, and means for introducing air under pressure into said liquid.

14. In apparatus for lapping gears of the type comprising mechanism for imparting relative motion to a lap member and a gear member having intermeshed tooth portions, a support for a lap member, a catch basin disposed therebeneath, and means for moving said catch basin vertically.

15. In apparatus for lapping gears of the type comprising mechanism for imparting relative motion to a lap member and a gear member having intermeshed tooth portions, a frame member, a lap support carried by said frame member, a catch basin carried by said frame member and disposed beneath said lap support, and means associated with said frame member for moving said catch basin vertically.

16. In apparatus for lapping gears of the type comprising mechanism for imparting relative motion to a lap member and a gear member having intermeshed toothed portions, the combination with means for applying torque to said members to establish circumferential pressure between the toothed portions thereof, and automatic means for determining, in advance of a series of operations on a succession of gear members, the maximum amount of material to be removed from any one tooth of any of such gear members, said means including devices operatively associated with said first named means for interrupting the application of such torque thereby on completion of a predetermined relative rotative displacement of said members resulting from the removal of material from the toothed portions.

17. In apparatus for lapping gears of the type comprising mechanism for imparting relative motion to a lap member and a gear member having intermeshed toothed portions, the combination with means for applying substantially constant and predetermined torque to said members to establish circumferential pressure between the toothed portions thereof, and automatic means for determining, in advance of a series of operations on a succession of gear members, the maximum amount of material to be removed from any one tooth of any of such gear members, said means including devices operatively associated with said first named means for interrupting the application of such torque thereby on completion of a predetermined relative rotative displacement of said members resulting from the removal of material from the toothed portions.

18. In apparatus for lapping gears of the type comprising mechanism for imparting relative motion to a lap member and a gear member having intermeshed toothed portions, the combination with automatic means for effecting relative rotation of said members to the extent required to engage one working face of the teeth of the gear member with the opposed working face of the teeth of the lap member and for applying pressure between the said engaged tooth faces, of means operatively associated with said

first named means for interrupting such application of pressure thereby on completion of a predetermined relative rotative displacement of said members resulting from the removal of material from the toothed portions thereof.

19. In apparatus for lapping gears of the type comprising mechanism for imparting relative motion to a lap member and a gear member having intermeshed toothed portions, the combination with automatic means for effecting relative rotation of said members to the extent required to engage one working face of the teeth of the gear member with the opposed working face of the teeth of the lap member and for applying pressure between the said engaged tooth faces, of means operatively associated with said first named means for interrupting such application of pressure thereby on completion of a predetermined relative rotative displacement of said members resulting from the removal of material from the toothed portions thereof, said second named means acting independently of the initial tooth clearance in interrupting the application of pressure by said first named means.

20. In apparatus for lapping gears of the type comprising mechanism for imparting relative motion to a lap member and a gear member having intermeshed toothed portions, the combination with means for effecting relative rotation of said members to the extent required to engage one working face of the teeth of the gear member with the opposed working face of the teeth of the lap member and for applying pressure between the said engaged tooth faces, said means including an element displaceable through a distance determined by the extent of relative displacement required to engage the cooperating tooth faces of the lap and gear members, a second element displaceable with said first element in engaging the said tooth faces, and means for further displacing said second element with respect to said first element to an extent sufficient to maintain the pressure between the engaged faces during removal of material therefrom, and means for limiting the extent of displacement of said second element, whereby the amount of material removed from the opposed tooth faces of said members may be predetermined.

21. In apparatus for lapping gears of the type comprising mechanism for imparting relative motion to a lap member and a gear member having intermeshed toothed portions, the combination with an energy storing device operatively connected with at least one of said members to apply continuous circumferential pressure between the toothed portions of said members, of means including a fluid pressure device acting independently for effecting relative rotative movement of said members to engage opposed working faces of the teeth thereof, said fluid pressure device being operatively connected to said energy storing device to supply energy to the latter.

22. In apparatus for lapping gears of the type comprising mechanism for imparting relative motion to a lap member and a gear member having intermeshed toothed portions, the combination with an energy storing device operatively connected with at least one of said members to apply circumferential pressure between the toothed portions of said members, of a fluid pressure device for effecting relative rotative movement of said members to engage opposed working faces of the teeth thereof, said fluid

5 pressure device being operatively connected to said energy storing device to supply energy to the latter, and means whereby said fluid pressure device is rendered inoperative while said energy storing device is operating to supply pressure between said members.

10 23. In apparatus for lapping gears of the type comprising mechanism for imparting relative motion to a lap member and a gear member having intermeshed toothed portions, the combination with an energy storing device operatively connected with at least one of said members to apply circumferential pressure between the toothed portions of said members, of means separate from said mechanism and including a fluid pressure device comprising an element displaceable in response to fluid pressure to an extent sufficient to supply energy to said energy storing device and to effect contact between opposed 15 working faces of said members, and means for retaining said element against further displacement during operation of said energy storing device.

20 24. In apparatus for lapping gears of the type comprising mechanism for imparting relative motion to a lap member and a gear member having intermeshed toothed portions, the combination with means for applying torque to said members to establish continuous circumferential pressure 25 between the toothed portions thereof, of means separate from said mechanism and including a fluid pressure actuated device for initiating operation of said first-named means.

30 25. In apparatus for lapping gears of the type comprising mechanism for imparting relative motion to a lap member and a gear member having intermeshed toothed portions, the combination with means including a spring for applying torque to said members to establish continuous circumferential pressure between the toothed portions thereof, of means separate from said mechanism and including a fluid pressure actuated device for loading said spring.

35 26. In apparatus for lapping gears of the type comprising mechanism for imparting relative motion to a lap member and a gear member having intermeshed toothed portions, the combination with means including a spring for applying torque to said members to establish continuous circumferential pressure between the toothed portions thereof, of means separate from said mechanism and including a fluid pressure actuated device for compressing said spring to a predetermined extent only.

40 27. In apparatus for lapping gears of the type comprising mechanism for imparting relative motion to a lap member and a gear member having intermeshed toothed portions, the combination with means including a spring for applying torque to said members to establish continuous circumferential pressure between the toothed portions thereof, of means separate from said mechanism and including a fluid pressure actuated device for compressing said spring to a predetermined extent only, and means for limiting the expansion of said spring.

45 28. In apparatus for lapping the teeth of externally toothed gears, the combination with a lap support, of an internally toothed lap carried in fixed position by said support, a frame having a portion extending above said support, a shaft supported on said frame for substantially vertical reciprocatory movement and for rotation about a substantially vertical axis, said shaft having a portion adapted to support a gear to be

lapped in meshing relation with said lap, means associated with said frame for guiding said shaft to cause the gear to follow the lap teeth during reciprocatory movement of said shaft, and means for rotating said shaft to provide circumferential pressure between the teeth of the gear and lap, said last named means being disposed sufficiently close to the gear to avoid undesirable torsional springing of said shaft.

29. In apparatus for lapping the teeth of external helically toothed gears, the combination with a lap support, of an internally toothed lap carried in fixed position by said support, a frame having a portion extending above said support, a shaft supported on said frame for substan-

10 tially vertical reciprocatory movement and for rotation about a substantially vertical axis, said shaft having a portion adapted to support a gear to be lapped in meshing relation with said lap, means associated with said frame for imparting rotation to said shaft during reciprocatory movement to cause the gear teeth to follow the lap teeth, and means associated with and acting through said first means for rotating said shaft to provide circumferential pressure between the teeth of the gear and lap, said last named means being disposed sufficiently close to the gear to avoid undesirable torsional springing of said shaft.
